[57] CLAIM

The ornamental design for a specimen collection skirt, substantially as shown.

DESCRIPTION

FIG. 1 is a side elevational view of a specimen collection skirt embodying my new design;
FIG. 2 is a top plan view of the skirt of FIG. 1;
FIG. 3 is a front elevational view of the skirt of FIG. 1;
FIG. 4 is a rear elevation view of the skirt of FIG. 1;
and
FIG. 5 is a bottom plan view of the skirt of FIG. 1.
